UNITED STATES PATENT OFFICE.

AXEL LEVEDAHL, OF AURORA, ILLINOIS, ASSIGNOR TO INDEPENDENT PNEUMATIC TOOL COMPANY, OF CHICAGO, ILLINOIS, A CORPORATION OF DELAWARE.

PNEUMATIC TOOL.

Application filed July 30, 1919. Serial No. 314,374.

To all whom it may concern:

Be it known that I, AXEL LEVEDAHL, a citizen of the United States, residing at Aurora, in the county of Kane and State 5 of Illinois, have invented new and useful Improvements in Pneumatic Tools, of which the following is a specification.

This invention relates to improvements in pneumatic tools and more particularly to sand rammers of the floor type, and consists 10 in the matters hereinafter described and claimed.

In the drawings:—

Fig. 1 is a side elevational view of a pneumatic sand rammer embodying the features 15 of my invention;

Figs. 2 and 3 are, when considered collectively, a longitudinal sectional view through the sand rammer, on a scale somewhat 20 greater than that shown in Fig. 1;

Fig. 4 is a longitudinal sectional view through the throttle stem of the rammer.

Fig. 5 is a side elevational view of the combined piston and plunger with one end 25 thereof broken away to illustrate a detail of construction;

Fig. 6 is a transverse sectional view taken on line 6—6 of Fig. 4;

Fig. 7 is a perspective view of the throttle 30 valve stem;

Figs. 8 and 9 are transverse sectional views taken on lines 8—8 and 9—9 respectively, of Fig. 2;

Fig. 10 is a side elevational view of the 35 locking pin and its spring;

Fig. 11 is a longitudinal sectional view taken on line 11—11 of Fig. 1;

Fig. 12 is a transverse sectional view taken on line 12—12 of Fig. 11; and

Fig. 13 shows the manner in which the cap 40 of the valve block is applied thereto.

A sand rammer embodying the features 45 of my invention comprises a barrel 1 on one end of which is threaded a valve housing or head 2. Said barrel has the usual bore 3 for a reciprocating piston 4, provided with a rod 5 which extends beyond the opposite end of said barrel and has removably connected therewith a stamper or 50 plien 6. Said barrel is provided with the usual passages 7 for the operating fluid, the admission and exhaust of which to and from the barrel, on opposite sides of the piston, being controlled by a valve 10 in the block

8 in the housing or head 2 as in pneumatic 55 tool design. A cap or disc 9 closes the adjacent ends of the block 8 and the barrel 1. The valve block 8 and the disc 9 are held in alignment with the barrel at one end, and a shoulder 11 in the head 2, prevents end- 60 wise displacement of the parts in that direction. The said valve block 8 has a tubular extension 8^a, provided at its outer end with an annular, undercut groove 8^b into which is forced a concave cap 8^c, as shown in Fig. 13. 65 Said cap 8^c is flattened out to fit snug and air tight in said groove and closes the end of the extension. The piston valve 10 has a cylindrical extension 10^a which fits air tight 70 in the tubular extension 8^a and is fed with live air through radial ports 8^d which communicate at all times with the live air supply. Thus there is a live air pressure constantly on the valve extension 10^a. This tends to continuously force the valve forward, but as said valve is reversed by reason of the pressure on its larger pressure area, the live air in the valve block extension 8^a is forced back into the supply, and thus no live air is lost in this operation, except what might leak through, in case the valve becomes worn. In connection with the ports 8^d, I provide in the valve block other radial ports 8^e which open into the valve bore in the block. These ports take 75 care of leakage at this point and also relieve the vacuum formed at this point when the valve 10 moves forwardly.

The piston 4 is made hollow, for the purpose of lightness, and in its open top end is provided an annular, undercut recess 12 into which is forced a concave cap or disc 13, which when flattened out, is locked against displacement. Figure 5 shows the cap 13 before it is forced into the recess 12, 80 and Figure 2 shows said cap after it has been forced into and flattened out in said recess. The piston rod 5 extends through a stuffing box 14 at the bottom of the barrel. To hold the piston 4 and its rod 5 against 85 rotation in the barrel, the rod 5 is provided with a plurality of longitudinally extending, concave flutes or grooves 15, 15, and the hole through the stuffing box 14 has a corresponding shape to prevent rotation of the piston. The stuffing box 14 includes a metallic inner ring 16 engaging against a shoulder 17 at 90 that end of the barrel. There is a second 95

ring 18 having an outwardly projecting, radial lug 19 (see Fig. 9) extending into a longitudinal groove 20 in the barrel 1. Between said rings are interposed compressible gaskets 21, 21, preferably made of leather. The rings and gaskets are provided with parts which extend into the flutes 15, 15, as shown in Fig. 9. A nut having a screw body 22 threaded into the forward end of the barrel, acts to force the ring 18 towards the ring 16 and compress the gaskets between them. The head 23 of the nut is beyond the end of the barrel and has a hole 24 (Fig. 1) in its periphery to receive a spanner wrench or other device to tighten or loosen the nut. To lock the nut in any of its adjusted positions, I provide in the face of the nut towards the end of the barrel, a plurality of circumferentially spaced, countersunk depressions 25, 25, as shown in Figs. 2 and 8, and which co-operate with a locking pin 26 projecting beyond the end of the barrel and having a conical shaped outer end to enter any one of said depressions 25 and to ratchet therewith, in the turning of the nut. Said pin 26 slides in a recess 27 formed in the end of the barrel 1. The inner end of said pin is reduced to receive a coiled expansion spring 28, which forces the pin outwardly. The last two loops at the inner end of the spring are made of a diameter slightly greater than that of the recess 27, to hold the spring therein, and as the loops at the opposite end 35 of the spring tightly engage about the adjacent end of the pin 26, the latter and the spring are prevented from dropping or being projected out of the recess 27. Near the outer end of the pin 26, is a groove 29 to permit a screw driver or other implement to be engaged with the pin to loosen the same should it bind in said recess 27. After the nut has been tightened, the pin will engage in the same and hold the nut from accidental rotation.

To lock the head or valve housing 2 to the barrel 1, I provide the following construction. Said barrel 1 is provided adjacent its upper end with an annular rib 31 against which bears a locking ring 32, surrounding the barrel. Interposed between said ring 32 and the opposed end of the housing 2, is a coiled expansion spring 33 surrounding the barrel and having its ends 50 bent in opposite directions to enter pockets or recesses 33^a, 33^b in the ring and head respectively, as shown in Fig. 1. In that face of the ring 32 opposed to the rib 31 is a plurality of ratchet teeth 34 (Fig. 12), between two of which the tooth 35 (Fig. 11) of a locking key 36 engages. Said key 36 is in the form of a plug having its base circular to seat in a correspondingly shaped socket in the barrel 1 at the rib 31, as shown in Figs. 11 and 12. Said key has a slotted

head by means of which it may be rotated by a screw driver to release its tooth 35 from locking engagement with the teeth of the ring 32. In the periphery of said ring 32 is provided a plurality of holes 32^a for 70 a spanner wrench or the like, to rotate said ring to increase or decrease the tension of the spring 33. As is apparent, this construction prevents any rotation between the barrel and head until it is desired to remove 75 one from the other for the purpose of inspection or repair.

The throttle stem or casing 36 for the rammer, is tubular and is connected by a tube 37 with the valve housing 2 in any preferred manner. The upper end of said stem 36 is threaded to permit an air supply hose to be connected therewith. Said throttle stem 36 is provided between its ends with a bore arranged at an inclination to the 85 longitudinal axis of said stem and in which is located a tubular bushing 38. Said bushing 38 is provided with a valve seat 39 for a ball valve 40, which is normally held against said seat by a spring 41 interposed 90 between the same and a screw plug 42 closing one end of said bushing. The opposite end of said bushing 38 is reduced and receives a valve stem 43 resting at one end on said ball valve and projecting at its other 95 beyond said bushing, as shown in Figs. 3 and 4. Said stem 43 is provided with an annular groove 44 which normally registers with ports 45 and 46 in the bushing and throttle stem respectively. Said valve stem 100 43 is provided with a groove 47 connecting the groove 44 with the space around the reduced part 48 of said stem, so that when the ball valve is closed, any leakage of air to the atmosphere is through the groove 47 and 105 ports 45 and 46, thus guarding against accidental operation of the rammer, due to leakage between the ball valve and its seat. The bushing 38 is provided with two ports 49 and 50 on opposite ends of the valve seat 39 110 and in substantial alignment with the longitudinal axis of the passageway through the throttle stem as shown.

The valve stem 43 is moved endwise in a direction to open the ball valve 40 by a 115 single, one-piece lever 51 extending along the throttle stem 36 and across the valve stem 43. Said lever 51 has one end positioned between the throttle valve 40 and the valve housing 2 and is there pivoted to the 120 throttle stem 36 by a stud or pin 52. Said lever 51 is provided between its ends with an offset portion or hood 53, arranged at right angles to the valve stem and made to enclose and contact against the upper or 125 outer end of the same. Pivoted secured to the throttle stem 36 at the free end of the lever 51, is a bail 54, adapted to be swung over the free end of said lever to hold the 130 same in contact with the throttle stem and

the ball valve 40 open. When the lever 51 is released from the bail 54, the spring 41 acts to close the ball valve against its seat and to return the lever into its normal position, as shown in Fig. 3, where the rear end 51^a of said lever engages against the throttle stem and limits the outward movement thereof.

Located in the valve housing 2 in advance 10 of the valve block 8, there is a strainer or screen 55 to prevent scale and the like from entering the ports and passages in the valve block 8, the screen being held in place by an expansive split ring 56.

15 By connecting the throttle stem 36 with the barrel 1, the tool as a whole has such a length that it permits the operator to handle the tool while standing in an erect position and yet allow the stamper 6 at the lower end 20 of the tool, to reach the mold on the floor. The operator grasps the tool about its throttle stem 36 above the throttle valve 40, and draws the free end of the lever 51 against and into contact with the throttle stem, 25 thereby opening the ball valve 40. The lever 51 may be held in such position, independent of the operator's hand, by the bail 54. The lever 51 has a transverse curvature corresponding to the contour of the throttle stem 36 so as to fit against the same and permit 30 the hand of the operator to grasp it while holding the tool in an easy and natural manner.

The construction above described, 35 possesses many advantages. A straight live air passage is provided through the throttle stem and with the throttle valve stem set at an inclination thereto, the width or thickness of the stem is materially reduced at this point, thereby producing a neat and 40 compact arrangement of parts and giving the tool a substantially uniform diameter throughout its entire length convenient for grasping. Furthermore, the ports 49 and 45 50, in said bushing, are substantially in line with the said passageway in the throttle stem, so that when the ball valve is moved away from its seat, the live air travels in a straight path. The hood 53 of the lever 50 55 shields the valve stem and acts to prevent

the entrance of sand or grit at this point and protects the same from abrasive action.

While in describing my invention, I have referred to certain details of construction 55 and arrangement of parts, as included in a sand rammer, I do not wish to be limited thereto, as the invention may readily be embodied in other types of pneumatic tools where its peculiar characteristics make it 60 advantageous to do so.

I claim as my invention:

1. A throttle valve, comprising a substantially straight tubular casing having a substantially straight live air passage extending 65 longitudinally therethrough, a bushing in said casing intermediate the ends thereof and extending across said passage at an inclination thereto, said bushing having ports opening into said passage on opposite sides 70 of said bushing and being aligned with each other and with the longitudinal axis of said passage, a valve seat in said bushing between said ports, a self closing valve in said bushing, and a pivoted lever on the outside of 75 said casing and engaging said valve for opening the same upon moving said lever toward said casing.

2. A throttle valve, comprising a tubular casing having a live air passage extending therethrough, as self closing valve mounted in said casing intermediate the ends thereof and having a stem projecting outside of 80 said casing, a seat in said passage for said valve, a lever pivoted to said casing on the 85 outside thereof at one side of said valve and extending over and engaging said stem for opening said valve upon moving said lever toward said casing, said lever having a transverse curvature corresponding to the 90 contour of said casing for allowing the lever to be in contact therewith when holding the valve open, and a bail pivoted on said casing adjacent the free end of said lever for engaging the same and holding the lever 95 against the casing.

In testimony that I claim the foregoing as my invention, I affix my signature this 26 day of July, A. D. 1919.

AXEL LEVEDAHL.
